BOX GUIDE FOR LOOM LAYS

Application filed November 22, 1928. Serial No. 321,204.

This invention relates to improvements in box guides used on the lays of fancy or drop box looms and it is the general object of the invention to provide ready means for setting 5 the boxes so they will deliver the shuttle correctly with respect to the reed.

In the usual box loom the lay is constructed of a wooden beam to the ends of which may be secured a so-called lay end made preferably of malleable iron.

The box end of a fancy loom lay usually employs a rather large casting secured to the lay sword and lay beam and having guides extending vertically in which slide the 15 tongues of the shifting boxes. These guides as ordinarily constructed have been made immovable with respect to the lay end and it has been necessary to move or bend the latter whenever an adjustment of the guides was 20 required. There is ordinarily no support for the outer end of the lay so that there may be a considerable length of metal extending beyond the crank and lay sword which is unsupported and therefore tends to move back 25 and forth due to its momentum as the lay reaches the rear and front extremities of its motion. It is found that in certain instances this tendency on the part of the lay end to move relatively to the lay beam results in in- 30 correct alignment of the box back, a condition which can be corrected in present constructions only by a rather awkward procedure of either bending the whole lay end relatively to the lay beam or taking down 35 the lay end and changing its position by the insertion of shims. It is an important object of my present invention to provide a box guide which shall be separate from and movable back and forth relatively to the lay end 40 so that the boxes may be quickly and easily positioned relatively to the reed line.

The back of the box ordinarily is not in true alignment with the reed as such a construction might result in causing the shuttle 45 to fly out of the loom. In order to prevent

this action on the part of the shuttle the outer end of the box back usually lies slightly forward of the reed line, this construction tending to push the shuttle toward the reed to be held in contact with the latter throughout its flight through the shed. Because of varying conditions of warp or different widths in the wires of which the reed dents are made it is desirable to be able to adjust the angularity of the box back relatively to 50 the reed and it is a further object of my present invention to provide means to permit readily this adjustment.

I have shown herein means for varying the outer guide of the box but the principle 60 set forth herein may be equally applicable to the inner guide near the reed and I do not wish to be limited to the particular form of my invention as shown herein.

With these and other objects in view which 65 will appear as the description proceeds, my invention resides in the combination and arrangement of parts hereinafter described and set forth in the claims.

In the accompanying drawings wherein I 70 have shown two forms of the invention,

Fig. 1 is a front elevation of one end of a lay having my invention applied thereto,

Fig. 2 is a top plan view of Fig. 1 showing 75 the outer portion of the lay, and

Fig. 3 is a top plan view of Fig. 1, showing 80 the inner and central portions of the lay, parts being removed and others being shown in section for the sake of clearness.

Referring to Fig. 1, I have shown a loom- 85 side 10 and a rocker shaft 11 to the left end of which is secured the rocker iron 12. A lay sword 13 moves around the axis of the rocker shaft 11 and extends upwardly to have secured thereto the lay beam 14 which may be made of wood. As shown particularly in Fig. 2 there extends to the left of the lay wood a lay end member 15 to which is secured a block 16. Said block has attached to the forward face 17 thereof a plate 18 which for 90

the most part is of the usual construction. The lay is provided adjacent the reed R with a guide 19 having a vertical slot 20 which receives a complementarily formed 5 tongue 21. Said tongue is on the inner end of the gang of boxes B and guides the latter. The reed R defines the path along which the shuttles should move across the loom and the boxes which may be formed as a single 10 integral casting are provided with a common back 22, the forward wall 23 of which is to be kept in proper relation with respect to the reed R. The boxes may be reciprocated by a rod 24 operated by mechanism not 15 shown but acting through a link 25 and the shuttles when brought to position one at a time may be propelled by the picker stick 26.

During the normal running of the loom the 20 boxes B will be moved in a vertical direction so that the tongue 21 will move in the slot 20 of the guide 19, thereby holding the inner end of the boxes in correct position with respect to the reed. The matter thus far described forms no part of my present invention and may be of usual construction.

In carrying my present invention into effect I provide the plate 18 with a rear vertical extension 40 and provide for the latter 30 a movable guide element 41. The latter is formed with a slot 42 somewhat similar to the slot 20 and guide 19, said slot 42 receiving the tongue 43 of the boxes. The guide element 41 is separate from the plate 18 and 35 its vertical extension or projection 40 but is held to the latter by means of a pair of bolts 44 and 45 which are located respectively at the upper and lower ends of the guide plate 18.

40 Each of the bolts 44 and 45 passes through a horizontal slot 46 formed in the rear extension 40 and the head of the bolts are sufficiently large to prevent passing of the latter through these slots. The inner or right ends 45 of the bolts are threaded into the element 41 as shown at 47 in Fig. 3.

The bolts 44 and 45 are movable horizontally in and held against movement in a vertical direction by the slots 46 and said bolts 50 are positioned by adjusting screws 48 and 49 located respectively behind and in front of the plate 18. As shown clearly in Fig. 3 the upper adjusting screws are in contact with the screw 44 serving to position the latter 55 and therefore the guide element 41 with respect to the reed and also tending to prevent rotation of the bolt 44 which would disturb the proper setting of the guide element. The same relation exists for the lower bolt 45 and 60 the adjusting screws for both bolts may be held in position by lock nuts 50.

When assembling the parts shown particularly in Fig. 3 the guide element is secured to the extension 40 before the boxes B 65 are put in place and given an approximate

setting in a horizontal direction. The boxes may then be placed as shown in Fig. 3 with the tongues 21 and 43 in their respective guide slots and a gauge applied to the box to determine its relative position with respect to the reed. If the outer end of the box is forward too far with respect to the reed the rear screws 48 may be turned backwardly and the front screws 49 turned to move the bolts 44 and 45 rearwardly until the surface 70 23 of the boxes assumes the proper relative position with respect to the reed R. When in correct position the rear screws 48 may be set up tightly against the bolts 44 and 45 and the lock nuts 50 moved to position to hold all 75 of the several parts rigidly in proper position. Should the outer end of the boxes be behind the improper position the corresponding adjustment may be made, the element 41 being moved relatively to the extension 40 80 and being held in adjusted position by the bolts and screws.

If during the running of the loom it is noticed that the shuttle flies out of the shed because of the fact that the outer end of the box is behind its correct position, the element 41 may be moved forwardly in the manner described. Conversely, if it is noticed that the rear shuttle is wearing too much because the angle between the surface 23 and the reed 90 had become too great the element 41 can be moved rearwardly. It will be noticed that the positioning of the boxes with respect to the reed is accomplished without bending the lay end 15 and without disturbing the relative position of the block 16 and plate 18 with respect to the lay beam 14.

From the foregoing it will be seen that I have provided a very simple means for varying the angular position of the boxes 105 with respect to the reed without requiring bending of the lay end or resetting of the same with respect to the lay beam. It will also be seen that the guide element can be moved to a plurality of positions and that when in a final position is held tightly against an extension 40 by means of bolts 44 and 45 and it will further be seen that the latter are held against rotation and are therefore locked in their proper position by the adjusting screws 48 and 49. While I have shown the guide element as being movable relatively to the lay and located on the outer end of the boxes yet I do not wish to be limited to this 110 particular location of the movable guide element. Furthermore, the portion of the construction which is moved to secure correct alignment is supported directly by the lay and the tongue which cooperates therewith 115 is integral with the boxes, but I do not wish to be limited to this construction as it is within the scope of my present invention to provide an adjustable connection between the box and the lay in the form of a movable ele- 120 125 130

ment which may be secured either to the box or the lay end.

Having thus described my invention it will be seen that changes and modifications may be made therein by those skilled in the art without departing from the spirit and scope of the invention and I do not wish to be limited to the details herein disclosed, but what I claim is:

1. In a loom, a lay, shifting shuttle boxes movable relatively to the lay, a guide having a surface transverse of the lay for one end of the boxes to determine the direction of movement of the latter relatively to the lay, and means carried by the lay having a surface transverse of the lay to engage the first transverse surface to give said guide a plurality of positions relatively to the lay to give said boxes a plurality of angular positions relatively to the lay.

2. In a loom, a lay, shifting shuttle boxes movable relatively to the lay, a vertically extending guide for the boxes to determine the path of movement of the latter relatively to the lay, a mounting for said guide fixed to the lay, and threaded means extending transversely of the lay to operatively connect the mounting and guide to render the latter movable relatively to the lay to cause the guide and boxes to assume a plurality of positions relatively to the lay.

3. In a loom, a lay, shifting shuttle boxes movable relatively to the lay, a reed extending vertically from the lay, a guide having a surface transverse of the lay for the boxes substantially parallel to the reed, and means secured to the lay having a surface transverse of the lay to engage the first transverse surface to support said guide in a plurality of positions relatively to the reed to give said boxes a plurality of angular positions relatively to the reed.

4. In a loom, a lay, shifting shuttle boxes movable relatively to the lay, a reed extending substantially vertically from the lay, a plate carried by the lay, a guide member having a substantially vertically extending groove secured to the plate, said guide cooperating with the boxes to determine the path of movement of the latter, and connections between the guide member and the plate whereby the latter may assume a plurality of positions relatively to the lay to give the boxes a plurality of angular positions with respect to the reed.

5. In a loom, a lay, shifting shuttle boxes movable relatively to the lay, a reed extending across the lay, a guide member supported by the lay and having means to cooperate with the boxes to determine the path of movement of the latter, supporting members secured to the guide and extending through a portion of the lay, and a guide member holding means supported by the lay and in contact with the supporting members to give the latter and the

guide a plurality of positions relatively to the lay to cause the boxes to assume a plurality of angular positions with respect to the reed.

6. In a loom, a lay, shifting shuttle boxes movable relatively to the lay, a reed extending across the lay, a plate carried by the lay, a guide element cooperating with the boxes to determine the path of movement of the latter relatively to the lay, a screw member extending from the guide element through the plate, and means carried by the plate and in engagement with the screw member to give the latter a plurality of positions relatively to the lay so that the boxes may be disposed in a plurality of angular positions with respect to the reed.

7. In a loom, a lay, shifting shuttle boxes on the lay, a reed extending across the lay, a plate secured to the lay, a guide element to cooperate with the boxes to determine the path of movement of the latter, a screw secured in and moving with the guide element and extending through and movable with respect to the plate, and opposing screws to engage opposite sides of the first named screw to move the latter and consequently the guide element relatively to the plate, whereby the boxes may be caused to assume a plurality of angular positions relatively to the reed.

8. In a loom, a lay, a shifting shuttle box member movable relatively to the lay, a plate member fixed to the lay, and a guide element to determine the path of movement of the shuttle box member relatively to the lay, said element being secured to one of the members and being capable of assuming a plurality of positions with respect to said member to which it is secured to give the box member a plurality of positions relatively to the lay.

9. In a loom, a lay having a reed, a member fixed with respect to the lay, a shifting shuttle box member movable relatively to the lay, and a guide element to cooperate with one of said members to determine the path of movement of the shuttle box member and being capable of attachment to the other member in a plurality of positions toward and from the reed line in order to give the shuttle box member a plurality of angular positions relatively to the reed.

10. In a loom, a lay having a reed, a shifting shuttle box member movable with respect to the lay and in a direction substantially parallel to the reed, guide means having a surface transverse of the lay carried by the lay, and means to secure the guide means having a surface transverse of the lay to engage the first transverse surface to the lay in a plurality of positions relatively to the lay to vary the position of the shuttle box member in a direction transverse of the reed, whereby the shuttle box member may assume a plurality of positions relatively to the reed.

11. In a loom, a lay, shifting shuttle boxes movable relatively to the lay, a vertically extending guide for the boxes to determine the

path of movement of the latter relatively to the lay, a mounting for said guide fixed to the lay, and attaching means operatively connecting the mounting and guide and movable transversely of the lay to assume a plurality of positions relatively to the mounting to cause said guide and boxes to assume a plurality of positions transversely of the lay.

In testimony whereof we have hereunto
10 affixed our signatures.
